UNITED STATES PATENT OFFICE.

RALPH B. WAKEFIELD, OF SPRINGFIELD, MASSACHUSETTS.

COOKING DEVICE.

SPECIFICATION forming part of Letters Patent No. 224,252, dated February 3, 1880.

Application filed October 2, 1878.

To all whom it may concern:

Be it known that I, RALPH B. WAKEFIELD, of Springfield, in the State of Massachusetts, have invented a new and useful Cooking Device; and I do hereby declare that the following is a full, clear, and exact description thereof, reference being had to the accompanying drawing, making a part of this specification, and to the letters of reference marked 10 thereon.

My invention is designed for use upon the ordinary cooking-stoves, or upon any other having the ordinary circular hole or opening in the top, the object of the invention being 15 to shake the grate to clear the ashes from the fire, the dumping of the ashes from the ash-box without disturbing the fire, and the dumping of the whole contents of the fire-box of the device into the stove, when desired, without removing the device from its position on the stove in either case, all which will be more fully hereinafter described.

The drawing represents a central vertical section of my invention, showing the grate 25 dumped and the valve below the grate tilted and the draft open.

In the drawing, H represents a shell, cylindrical in form, and provided with a top ring, A'', and at the bottom with a plate, B, having 30 an opening, B', in which is suitably hung a valve, B''; and a flue-opening, B''', is also made to communicate with the flue behind the back-board L, which back-board extends across from one side of the shell to the other inside.

A represents the grate-ring, in which is suitably suspended a grate, D, which is so arranged that it may be shaken from one side to the other when in a horizontal position, or it may be tilted into the position shown in the 40 drawing when desired.

Suitable fire-brick may be placed around the inside of the shell or body from one end of the back-board around to the other, and a small door, C, may be arranged to slide in ways or guides made in the grate-ring A and in the plate B; or this door may be provided with pivots, so that it may swing outward.

The valve B' may be held in place in a horizontal position by any convenient means, and 50 the grate D may be prevented from tilting or dumping when in a horizontal position by a projection, c', on the inside of the draft-door C, which extends in beneath the edge of the grate when the door is shut, as shown in dotted lines, or by any other convenient means.

This device is used by removing one of the lids or covers over the fire-box of an ordinary stove and placing the device over the hole. The lid or cover removed from the stove may be placed on the top ring, A'', of the device, 60 and the grate and the valve beneath both being in a horizontal position, a fire is built on the grate, using for fuel either chips or coal, as desired. The draft-door C being open, the products of combustion pass up over the back-board L and down the flue behind the back-board, through the flue-opening, into the stove.

If the ashes should collect on the valve B'', the latter is tilted and the ashes fall into the fire-box of the stove below; and if the fire 70 should go out the whole contents of the fire-box of the device may be dumped into the fire-box of the stove by tilting both the grate D and valve B'' at once, so that it will not be necessary to remove the device from its position on the stove.

I am aware that furnaces intended to be used upon a stove or range have heretofore been made with a fixed grate, a fire-box, a draft or cold-air passage, and a diving-flue; 80 but in all the devices heretofore made it has been necessary, after the fire has gone out in them, to remove the cinders and ashes therefrom, either by picking them out with the hands or removing the furnace from its position on the stove or range, carrying it out, and turning it upside down. But I am not aware that a cooking device to be used upon a stove or range has ever heretofore been made having a fire-box, a diving or reversible flue, a dumping and shaking grate, and a valve opening beneath the grate, so that the ashes and cinders could be dumped out into the fire-box of the stove without removing the device from its position on the stove or range.

Having thus described my invention, what I claim as new is—

A cooking device consisting of a fire-box and a reversible flue located behind said fire-box, combined with a dumping and shaking 100 grate arranged in said fire-box, a valve arranged to open beneath said grate, and a flue-opening, B'', communicating with said reversible flue, said device being arranged and adapted to be used upon an ordinary stove or range, substantially as described.

RALPH B. WAKEFIELD.
